Inventor:

George Long

United States Patent Office.

GEORGE LONG, OF MARLBORO TOWNSHIP, OHIO.

Letters Patent No. 67,126, dated July 23, 1867.

IMPROVEMENT IN WAGON-BRAKE.

The Schedule referred to in these Letters Patent and making part of the same.

TO ALL WHOM IT MAY CONCERN:

Be it known that I, GEORGE LONG, of Marlboro township, in the county of Stark, and State of Ohio, have invented new and useful Improvements in Wagon-Brakes; and I do hereby declare that the following is a full, clear, and exact description thereof, reference being had to the annexed drawings forming a part of this specification, in which—

Figure 1 is an elevation of wagon, showing position of brake and attachments.

Figure 2 is a plan of running parts, showing position of levers, connecting links, &c., and

Figure 3 is a perspective, showing the position and action of anti-brake levers.

The nature of my invention consists in so constructing the wagon that the box may slide on the front bed-piece, and in so connecting the said front bed-piece with levers attached to the brakes as that on descending a declivity the front and rear parts of the running parts shall be brought nearer each other, and by so doing shall cause the brakes to bear on the wheels, and thus retard the movement of the load; and also in the use of anti-brake levers, whereby the apparatus before described shall be prevented from acting when the wagon is being backed.

To enable others skilled in the art to make and use my invention, I will proceed to describe its construction and operation.

A is the body of the wagon, B the wheels, C the axles, U the pole, T the coupling-pole. On the coupling-pole T is placed the board X, on which board is fastened the levers E E and I I by means of the bolts G G and H H. On one end of the levers E E are attached the brake-pieces F F, and their other extremities are attached to the levers I I. The other ends of the levers I I are attached to the connecting-links K K, which are attached to the front bed-piece D of the wagon. In this bed-piece D are fixed two rollers, S S, and in the end of the coupling-piece T is cut a slotted hole, N, through which the king-bolt passes. It will be readily seen that on going down a hill the hind and front axles will approach each other by means of the body A moving along on the rollers S, which it will be allowed to do by reason of the slot N in the coupling-piece T, and that by reason of such approaching the links K K will act on the levers I I, which in turn will act on the levers E E, causing the brakes F F to come in contact with the wheels B B, and thus retarding the motion of the wagon. It will also be seen that as soon as the power is again applied to the front axles they will separate further from the rear axles, producing an exactly opposite motion in the connecting-links and levers, and thereby removing the brakes from the wheels. The lever O in fig. 3 is attached to the side of the box A by the bolt a, and is connected at C with the lever P. This lever P is attached to the bottom of the box A by the bolt b, and the end d bears on the front bed-piece D. It will be seen that by holding the levers O and P in the position shown that the two axles would be prevented from coming nearer each other, so that the wagon could be backed without interference from the brakes, while with the levers in the position shown by the dotted levers O and P they could approach each other, and so cause the action of the brakes.

I do not claim as my invention the compound levers E I E I, or the brake-pieces F, as these are in common use; but what I do claim as my invention, and desire to secure by Letters Patent, is—

1. The peculiar combination and arrangement of the front bed-piece D, connecting-link K K, and compound levers E I E I, substantially in the manner and for the purpose specified; and

2. The peculiar combination and arrangement of the lever O with the lever P, forming a compound anti-brake lever, substantially in the manner and for the purpose specified.

GEORGE LONG.
